UNITED STATES PATENT OFFICE.

HARRY C. SCHLUETER, OF ST. LOUIS, MISSOURI.

SHOW-CASE CORNER FASTENER.

Application filed April 17, 1922. Serial No. 553,595.

To all whom it may concern:

Be it known that I, HARRY C. SCHLUETER, a citizen of the United States, residing in the city of St. Louis, State of Missouri, ⁵ have invented a certain new and useful Improvement in Show-Case Corner Fasteners, of which the following is a specification.

My invention relates to corner fasteners ¹⁰ for plate-glass show cases, and, is a distinct and practical improvement to overcome certain practical objections to, and defects in, corner pieces of the type making it necessary to drill holes in the glass to receive

¹⁵ screw fasteners.

The object of my present invention is to provide an upper corner plate including an inner cushion member capable of being drawn tightly into contact with the inner ²⁰ face of two upright glass panels and a horizontally disposed panel for firmly holding the panels in position at their corners between the corner plate and the cushion member.

²⁵ A further object of the invention is the provision of a screw-threaded member for drawing the cushion member in operative position.

³⁰ A further object of the invention is to provide a lower corner plate adjustably connected to the floor of the show case to accommodate any thickness of glass panel between the outer faces of the floor and the walls of the lower corner plate.

³⁵ A still further object of the invention is the provision of a tie-rod for connecting the cushion member of the upper corner plate with the lower corner plate to prevent any possible chance of the upright panels being ⁴⁰ lifted out of their corner sockets.

With the above and other objects in view, the invention consists in the novel features of construction, arrangement and combination of parts hereinafter more fully described and finally pointed out in the claims hereto appended.

Referring to the accompanying drawings forming a part of this specification, wherein like characters of reference denote similar parts throughout the several views:

Fig. 1, is a vertical sectional view of the upper and lower corners of a glass panel

show case provided with corner fasteners embodying my invention.

Fig. 2, is a plan view of the upper corner ⁵⁵ of a show case employing my corner fasteners.

Fig. 3, is a perspective view of the upper corner of a show case provided with my corner fastener.

Fig. 4, is a plan view of the cushion, or binding member which co-acts with the upper corner plate showing its engaging faces.

Fig. 5, is also a plan view of the cushion member.

Fig. 6, is a sectional view of the cushion member.

Fig. 7, is a top plan view of the lower corner plate fixed to a show case corner.

Fig. 8, is a bottom plan view thereof.

Referring to the accompanying drawings, the reference character 1 represents the floor of a show case, 2 the front glass panel, 3 the end, or side glass panel and 4 the top glass panel, which glass panels meet ⁷⁵ to form an upper corner, as shown in Figs. 1, 2 and 3, and, which glass panels 2 and 3 and the floor meet to form the lower corner of the show case, as shown in Figs. 1, 7 and 8.

5 indicates an upper corner plate having three walls so as to appear polygonal in shape. The walls of the corner plate, it will thus be seen from Fig. 3, will engage three glass panels, namely, the front panel ⁸⁵ 2, the end panel 3 and the top panel 4. The plate 5 is provided with an opening 6 at its apex, as shown in Fig. 1.

7 indicates a polygonally shaped cushion or binding member having the three triangular sides, or faces 8, 9 and 10 terminating in a truncated end, or apex 11. The cushion member 7 is provided with a central opening 12 terminating at the base of the cushion member in a socket 13. The cushion member is also provided with a channel 14 which communicates with the opening 12 and the socket 13, as clearly shown in Fig. 6. The three faces 8, 9 and 10 of the cushion member are each provided with the yieldable facings 15, 16 and 17, respectively, such as cork, rubber, or the like. These facings may be suitably fixed to the faces of the cushion member, as is manifest. The cush-

ioned faces of the cushion member 7 engage the inner faces of the glass panels 2, 3 and 4, as is evident from Figs. 1 and 2 of the drawing.

18 indicates a suitable screw, which is provided at its outer end with a head 19 for engaging the apex of the corner plate 5. The screw 18 passes through the opening 6 of the corner plate and through the opening 12 of the cushion member 7 and is provided with a nut 20 at its inner end which is seated in the square socket 13 in the base of the cushion member to prevent the nut from turning whenever the screw 15 is turned in either direction. It is evident that when the screw is turned in one direction, that it will draw the polygonally shaped cushion member tightly against the inner faces of three glass panels, thereby firmly holding the upper corner of the show case in proper position and alignment, as will be observed from Figs. 1 and 3. To permit the entrance of the screw into the opening 12 of the cushion member, it is only necessary to break away the extreme corners of the three glass panels, as at 21, to provide the necessary passage for the screw. By this arrangement, it obviates the necessity of drilling holes in the glass panels to receive fastening devices, such as screws, which are usually employed.

22 indicates the lower corner plate which also has three sides, or walls, so as to appear polygonal in shape. This corner plate 35 22 has one of its walls engaging the lower face of the floor 1 of the show case and is held in position by means of a bolt 23 which passes through an opening 24 in one wall of the corner plate and extends upwardly 40 through a slotted opening 1' in the corner of the floor 1. The bolt is provided with a head at its lower end which is seated in the counter sunk opening 25 of a bar 26 and the upper end of the bolt is provided 45 with a washer 27 and a nut 28 for firmly locking the corner plate in its adjusted, or proper position with relation to the floor 1 and glass panels 2 and 3. The upright side walls of the lower corner plate 22 are 50 spaced a suitable distance from the side or outer faces of the floor 1 to provide the sockets 29 and 30 for the glass panels 2 and 3, respectively, to stand in, as is evident from Fig. 7. The slotted opening 1' of 55 the floor 1 permits proper adjustment of the lower corner plate before tightening the nut 28, as is manifest. The bar 26 is held from rotary displacement by means of the bolt 31 which also anchors the bolt or screw 23, 60 as shown in Figs. 1 and 8.

To prevent any possible chance of some one lifting up on the top plate 4, or lifting the side and front panels from their sockets 65 and 30, respectively, should the panels be at all loosely held therein, I provide a

tie-rod 32 having a hook shaped upper end 33 adapted to engage in the channel 14 of the cushion member 7. The tie-rod 32 extends downwardly at the corner of the front and end panels 2 and 3 and the lower screw-threaded end 34 thereof passes through the slotted opening 1' of the floor and is provided with a shoulder nut 35 which engages the counter sunk opening 36 of bar 26 and passes through the opening 24' of the lower wall or side of the lower corner plate 22.

By tightening nut 35 it will be observed that the upper and lower corner plates are substantially tied together so that there is no danger of the front and side glass panels being lifted from their sockets between the floor 1 and the walls of the lower corner plate.

From the foregoing description, it is evident that by the use of my improved corner plates and associated parts, that I eliminate the boring of any holes in the glass panels and keep the glass panels in exact relation to form a true corner. A glass show-case employing my improved corner plates and fasteners, it will be observed, can be quickly set up without the assistance of skilled labor, as no boring of holes is necessary.

The many advantages of the herein described invention will readily suggest themselves to those skilled in the art to which it appertains.

I do not wish to be understood as having limited myself to the exact details of construction shown and described, but desire to have it understood that the invention I have shown in the drawings is merely illustrative, as it is manifest that various minor changes may be made in the exact construction and particular arrangement of parts without departing from the spirit of my invention, hence I reserve the right to make any such changes, or modifications as may fairly fall within the scope of the appended claims when fairly construed.

What I claim is:

1. In a glass panel show case corner fastener, in combination, a triangular lower corner plate having flat walls, a show case floor member having a corner slot with one end open, and a bolt passing upwardly through the lower wall of the corner plate and directed upwardly through the slotted opening of the floor member and provided with a hoop at its upper end for securing the corner plate in its applied position, said corner plate being adjustable through the medium of the bolt and slotted opening for providing glass panel receiving sockets of the size desired between the walls of the corner plate and the side faces of the floor member.

2. Corner fastening means for glass panel show cases consisting of an upper outer corner plate, an inner binding member,

means for holding said corner plate and said binding member in engagement with the outer and inner faces, respectively, of the front, end and upper glass panels of the show case, a lower outer corner plate, means for holding said corner plate in spaced relation with the floor of the show case to provide sockets for the front and end glass panels of the show case and means for connecting said upper and lower outer corner plates.

In testimony whereof, I have hereunto signed my name to the specification.

HARRY C. SCHLUETER.
